SHOE JACK

Euclid I. La Chapelle, Brockton, Mass.

Application June 28, 1939, Serial No. 281,573

3 Claims. (Cl. 12—127)

My invention relates to shoe jacks and more particularly to the type adapted to support a shoe, while on its last, by a toe-rest member, adapted to engage and support the forepart of the shoe and by a movable last-pin member, adapted to support the heelpart of the shoe and which is provided with a strong spring urging the last-pin member and the shoe downwardly and towards the toe-rest member to thereby firmly hold the shoe on the jack.

To accommodate shoes of various sizes, a shoe jack of this type is provided with a toe-rest member movable towards and from the last-pin member and having adjusting means whereby it may be held in set position relatively to the last-pin member. Thus several preparatory adjustments are necessary in jacking any ordinary case of shoes in the general run of a shoe factory.

With this type of jack, once the shoe has been placed on the last-pin member, the forepart of the shoe then is set upon the toe-rest member and in thus setting the forepart of the shoe, the toe-end of the shoe must be engaged and lifted up by the operator's left hand so as to move the movable last-pin member away from the toe-rest member against the tension of the aforesaid strong spring normally urging the same towards the toe-rest member. Thus, much physical effort is required in the setting of the forepart of the shoe on and in the removal of the shoe from the jack, which, in the aggregate of a day's work, becomes enormous and, notably so, when it is considered that all of this laborious work is being performed by the operator's left hand.

It is the main objective of my invention to provide a shoe jack of this general character, but so built and arranged that shoes of various sizes may be readily accommodated without need of any adjusting means and so built and arranged that shoes may be set on and removed from the jack more rapidly and with far less effort than heretofore possible and, even so when the tension of the aforesaid strong spring urging the last-pin towards the toe-rest member is much stronger than the usual tension of the spring on the ordinary jack.

As shown in the drawings:

Figure 1 is a side elevation of my improved shoe jack;

Figure 2 is a rear elevation of the said shoe jack;

Figure 3 is a detail view of my novel shoe forepart supporting member;

Figure 4 is a sectional detail view of the said shoe forepart supporting member;

Figure 5 is a plan view of the rocking frame, showing the slideways for the sliding block supporting the last-pin member and also shows the rocking frame moving member;

Figure 6 is a sectional detail view taken on line 6—6 of Fig. 1;

Figure 7 is a detail sectional view taken on line 7—7 Fig. 1;

Figure 8 is a detail view of the two brackets supporting the adjustable sliding support for the shoe forepart supporting member; and

Figure 9 is a detail view, partly in section, showing the adjustable column portion supporting the head of the jack and showing how the head may be rotated for adjusting the jack to any desired height preparatory to clamping the head supporting portion of the column in fixed position.

As further shown in the drawings:

My novel shoe jack comprises a floor base column 1, which supports the adjustable portion 2 of the column. The said floor base column having at its lower end, the external screw thread 3 which is threaded into the internal upper end of the floor base column 1 and is locked in set position when the desired height of the head of the jack has been determined, by the locking means 4 having the convenient handle 5. The upper adjustable column 2 is provided with the slots 6 and the clamping collar 7 which is clamped by the screw 8 and held in clamped condition by the lock 9. The said screw 8, being conveniently operated by the handle 10.

The head supporting member 11 has a downwardly projecting portion 12 which rotatably fits into the upper end of the column portion 2. A sole leather washer 13, preferably, is provided between the upper end of the column portion 2 and the flange portion 14 of the head supporting member 11. The said head supporting member has two upwardly extended bracket arms 15 and 16 which are integrally connected at their upper ends by the cross-bar 17 which supports the rearwardly extended arm 18 which carries the pivot 19 on which the rocking frame 20 is oscillatingly supported. Slideways 21, are provided upon the said rocking frame and extend rearwardly from the pivot 19. The said rocking frame 20 has a forwardly extended arm 22 which carries the pin 23 to which the upper end of a strong spring 24 is secured, its lower end being secured to the pin 25 which is provided in the lug 26 which extends upwardly from the head supporting member 11. The brackets 27 and 28 are secured to the bracket arms 15 and 16; the said bracket 27 extending

upwardly and having at its upper end the pivot-bolt 29 which supports the holding block 30. By loosening the set-nut 31 the said holding block 30 then may be set any desired angle and it 5 may be clamped in set position by tightening the set-nut 31. Thus, by this arrangement, the shoe forepart supporting member may be set so as to engage the toe portion of the shoe, as on ordinary jacks, instead of the back of the toe portion, as herein shown, in case the nature of the work being performed on the jacked shoe so required.

The said holding block also has the hole 32 through its entire length and it receives the rod 15 33 which may be held in adjusted position by the set-nuts 34. The shoe forepart supporting member 35 is secured to the upper end of the said adjustable rod 33. Mounted for free movement towards and from the shoe forepart supporting 20 member 35 in the slideways 21 of the rocking frame 20 is the sliding block 36 which carries the last-pin member or, in a broader sense, the shoe heelpart supporting member 37.

Towards the rear end of the slideways 21 I 25 have provided a novel moving means adapted to oscillate the rocking frame 20 and which consists of an upright post 38 which carries the forearm engaging member 39 whereby the rocking frame may be operated to rock upon the pivot 30 19 against the tension of the strong spring 24 under the influence of the pressure applied thereto by the operator preparatory to the setting of the shoe on and to the removal of the shoe from the jack. The length of the rocking frame from 35 the pivot 19, extending rearwardly, is such that the frame may be easily rocked against the tension of the strong spring 24 by the comparatively small degree of pressure being applied by the operator upon the forearm engaging member 39.

40 After the shoe has been placed upon the last-pin member 37 and moved, with the said member, towards the shoe forepart supporting member 35 to accommodate the size of the shoe relatively to the shoe forepart supporting member 35, the rocking frame 20, is then rocked and in thus being rocked, the last-pin member 37 is moved away from the shoe forepart supporting member 35 and the forepart of the shoe is elevated above the shoe forepart supporting member so that the 45 forepart of the shoe then may be easily set on or removed from the jack. In this connection, it is to be noted that in setting the shoe on and in removing the shoe from the toe-rest of the ordinary shoe jack, there is more or less frictional contact of the shoe with the toe-rest and thus liability of damage to a shoe having a delicate upper exists due to the fact that the operator's hand is unsteady in lifting up the toe-end of the shoe against the strong spring tension upon the last-pin member. This objectionable condition also 50 is eliminated by the use of my improved shoe jack.

It is to be further noted that the operator's hands are free to set the shoe on or to remove the 55 shoe from the jack and of all the laborious work now involved in the performance of these steps in the use of the ordinary shoe jack. Moreover, in providing manually operated moving means, and notably a forearm engaging member, such as 60 herein shown, the operator then may stand on

both feet at all times, which would be impossible were a foot treadle provided as a moving means.

My invention is not to be limited to the herein shown construction which may be varied within the scope of the appended claims, which are to be 5 interpreted broadly and limited only by the requirements of the prior art.

Each claim is to be interpreted as specifically stated therein.

Having thus explained the nature of my invention and shown the best form of embodiment now to me known, what I claim as new and desire to secure by Letters Patent of the United States is:

1. A shoe jack, having, a shoe forepart supporting member, a rocking frame; slideways in the 15 said rocking frame; a sliding block in the said slideways; a shoe heelpart supporting member mounted on the said sliding block; a spring connected to and urging the said rocking frame and the said shoe heelpart supporting member in a 20 direction towards the said shoe forepart supporting member, and a forearm engaging member, whereby the said rocking frame and the said shoe heelpart supporting member may be rocked against the tension of the said spring in a 25 direction away from the said shoe forepart supporting member, for the purposes described.

2. A shoe jack, having, a shoe forepart supporting member and a shoe heelpart supporting member, one of the said shoe supporting members being arranged for movements in a direction towards and in a direction away from the remainder of the said shoe supporting members; a rocking frame; slideways in the said rocking frame; a sliding block in the said slideways and 35 the said one of the shoe supporting members arranged for movement being mounted on the said sliding block; a spring connected to and urging the said rocking frame and the said one of the shoe supporting members arranged for movement, in a direction towards the remainder of the said shoe supporting members, and a forearm engaging member, whereby the said rocking frame and the said one of the shoe supporting members arranged for movement, may be rocked against the tension of the said spring in a direction away from the remainder of the said shoe supporting members, for the purposes described.

3. A shoe jack having, a shoe forepart supporting member and a shoe heelpart supporting member, one of the said shoe supporting members being arranged for movements in a direction towards and in a direction away from the remainder of the said shoe supporting members; a rocking frame and the said one of the shoe supporting members arranged for movement, being mounted on the said rocking frame; a spring connected to and urging the said rocking frame and the said one of the shoe supporting members arranged for movement, in a direction towards 50 the remainder of the said shoe supporting members, and a forearm engaging member, whereby the said rocking frame and the said one of the shoe supporting members arranged for movement, may be moved against the tension of the said spring and in a direction away from the remainder of the said shoe supporting members, for the purposes described.
